UNITED STATES PATENT OFFICE.

HARRY A. TRUSCOTT, OF WASHINGTON, DISTRICT OF COLUMBIA.

PARCEL-POST ENVELOP.

1,156,507.

Specification of Letters Patent. Patented Oct. 12, 1915.

Application filed November 10, 1914. Serial No. 871,372.

To all whom it may concern:

Be it known that I, HARRY A. TRUSCOTT, a citizen of the United States, residing at Washington, in the District of Columbia, have invented new and useful Improvements in Parcel-Post Envelops, of which the following is a specification.

This invention relates to improvements in envelopes, and particularly to an envelop which, while like or similar to the envelop in general use, includes or is provided with means for attaching it to a parcel post package in accordance with established regulations.

The primary object of the invention is to provide an envelop having an extension beyond the body thereof, and forming a portion of the blank from which the envelop is made, which extension is manifoldable into a plurality of plies for passage of a fastening, and thereby forming a tag whereby the fastening element may be secured to the envelop in a firm and secure manner and without liability of the envelop tearing under strain.

A further object of the invention is to provide an envelop having a manifoldable extension which may form a connection between the envelop body and sealing flap.

The invention consists of the features of construction, combination and arrangement of parts herein fully described and claimed, reference being had to the accompanying drawing in which:

Figure 1 is a back view of one form of envelop embodying my invention. Figs. 2 and 3 are sections on the lines 2-2 and 3-3 of Fig. 1. Fig. 4 is a plan view of the envelop blank. Fig. 5 is a back view of a slightly modified form of envelop. Fig. 6 is a similar view of another modified form of envelop. Fig. 7 is a section on line 7-7 of Fig. 6.

Referring to Figs. 1 to 4 inclusive, of the drawing, 1 designates the body or pocketed portion of an envelop formed by a front wall 2, end flaps 3 and bottom flap 4, which flaps are turned over upon the back of the front wall 2 and suitably united. The envelop is provided with the usual sealing flap 5, which, however, instead of being directly attached to the wall 2, as is usual in the ordinary form of envelopes, is connected with said front wall by an extension 6, integral with the blank of which the body of the envelop is formed. The said exten-

sion 6 is coextensive in width with the body or pocket 1 of the envelop, but in the illustration here given of substantially twice its depth, and includes bottom and top sections 7 and 8 foldable along a median line 9. As shown, the bottom section 7 is integral with the front wall 2, the top section 8 integral with the said bottom section 7 and the sealing flap 5 integral with the top section 8. The extension 6 is provided with the diagonally arranged fold or crease lines 10, extending across said extension 6, between the corner portions thereof and crossed or intersecting at an intermediate point in the length of the fold line 9, and said extension 6 is also provided with vertically arranged fold or crease lines 11 and horizontal transverse fold or crease lines 12 which intersect in the form of an approximately square figure near the center of the extension 6. The fold lines 11 extend between and intersect the fold lines 12 at points equidistantly above and below the fold line 9 and on opposite sides of the center of said line, while the fold lines 12 intersect and connect the upper and lower ends of the said fold lines 11. The sections 7 and 8 of the extension 6 may be provided with inturned flaps or flanges 13 and 14 designed if desirable, to be gummed or pasted to each other, or to sections 7 or 8 when the envelop is closed and sealed to connect and reinforce the said sections 7 and 8, and, if desired, the flaps or flanges 14 may be provided with extensions 15 adapted to be gummed or pasted to the back of the front wall 2 of the body 1 or infolded with portions of the body, to give greater security against tearing at the corners of the envelop from an unusual strain on the tag portion or against unauthorized attempts to open the sealed envelop.

In the manufacture of the tag portion of the envelop, the section 8 of the extension 6 is folded along the line 9 down upon the section 7, whereby the sealing flap 5 is brought into position for use, being gummed and ready to be pasted to the back of the body 1 to close and seal the pocket. The extension 6, after being thus folded upon itself is then folded along the registering diagonal crease lines 10 so as to provide double triangular infolds 16 which extend over upon the folded section 8, and then the upper or apex portion 17 of the triangular flap or tag thus produced is folded down

- upon the portion 16, said portions 8, 16 and 17 having been gummed, if desirable. The portions are then perforated and if desirable, fastened by an eyelet 18 as shown, 5 by means of which eyelet or eye the tag portion of the envelop may be fastened either directly to a binder cord passed around the package or to a cord or fastening wire designed to engage the binder cord.
- 10 In the use of the envelop the matter to be contained and inclosed is first inserted in the body or pocket 1 after which the mucilage on sealing flap 5 is moistened and the flap pasted down to close and seal the pocket 15 as in the ordinary envelop.
- It will be observed from the foregoing construction that the envelop will not only be securely sealed, but that the extension when multifolded in the prescribed manner 20 will provide a plurality of plies for the passage of the fastening member 18, by which a tag or fastening portion of maximum strength and durability is produced. As the eyelet passes through the large number 25 of folds of the paper, it will be apparent that it has a strong, durable and rigid connection with the envelop, so that liability of the tearing away of the envelop or of the fastening connection from the envelop will 30 be reduced to the minimum.

It will, of course, be understood that the multifold tag may be formed in other ways than that above disclosed, and that the portions may be united by any suitable fastening means.

In Fig. 5 I have shown a slightly modified form of construction in which the tag is arranged at one end instead of at the top of the envelop body, the general construction being otherwise the same. It is to be understood, of course, that the sealing flap or the tag, may be disposed at either end of the envelop body, or at the bottom or top, at will. I therefore do not confine myself, 45 in this particular, to the constructions and arrangements disclosed.

In the modified form of my invention shown in Figs. 6 and 7, the construction is substantially the same as that disclosed in 50 Figs. 1 to 4, inclusive, except that the apex 17^a of the triangular top fold 17^a is tucked under the portion 16 and united with the

remainder of the folds by the eyelet 18, thus further increasing the strength of construction. The fold extension 17^a may be a part 55 of the fold itself made by cutting on lines 11-11 and upper 12, or may be simply the point of the fold comprising the portion about one third of the way down from apex to base; and may be tucked under or laid 60 flat upon the portion 16.

I claim:

1. An envelop comprising a body portion having a sealing flap, and a substantially rectangular extension between said body portion and said flap, said extension being provided along its side edges with inturned flanges provided with free extensions having gummed faces, said extension being doubled so as to dispose the flap in sealing 70 position, and then folded from opposite sides on diagonal lines to provide portions, each composed of a plurality of thicknesses of material, and having said portions disposed in lapping arrangement, and fastening means passing through said lapping portions and uniting the same, said means being adapted for the passage of a fastening cord or thong, and said gummed flanges being adapted for attachment to each other 80 or to the plies of the extension and to have their extensions secured within the envelop body.

2. An envelop comprising a body portion having a sealing flap, and a substantially rectangular extension between said body portion and said flap, said extension being doubled by folding it on a line parallel with the body portion and so as to dispose the flap in sealing position, and then folded 90 from opposite sides on diagonal lines to provide portions, each composed of a plurality of thicknesses of material, and having said portions disposed in lapping arrangement, and fastening means passing through 95 said lapping portions and uniting the same, said means being adapted for the passage of a fastening cord or thong.

In testimony whereof I affix my signature in presence of two witnesses.

HARRY A. TRUSCOTT.
